UNITED STATES PATENT OFFICE.

EDWIN P. WALKER, OF MONROE, WASHINGTON.

COMBINATION FOLDABLE BOX AND TABLE.

1,253,913.

Specification of Letters Patent. Patented Jan. 15, 1918.

Application filed April 27, 1917. Serial No. 164,971.

To all whom it may concern:

Be it known that I, EDWIN P. WALKER, a citizen of the United States, residing at Monroe, in the county of Snohomish and 5 State of Washington, have invented certain new and useful Improvements in Combination Foldable Boxes and Tables, of which the following is a specification.

This invention relates to knock-down 10 folding boxes and pertains especially to a box so constructed as to be folded into an inclosing box, and to be unfolded for forming a table top and seats for a table.

The principal object of the invention is to 15 provide a foldable lunch or dinner box, especially for automobilists, which shall have its top, bottom and sides connected together so that the same elements constitute a serving board when unfolded in flat position.

A further object of the invention is to 20 provide a box embodying sides, top and bottom hinged together, and removable box ends constituting joining members for said 25 sides and bottom in folded position.

A still further object of the invention is to 30 provide in a combination box and table, specially constructed end members having sliding engagement with the top and side members so that upon removal of the end 35 members the other members are free to be unfolded in connected flat position.

The invention further embodies means for applying suitable legs and braces to 35 certain of said members for supporting the latter in table position, and the invention still further embodies the application of legs to the end members for utilization as seats or stands.

40 Various other objects, advantages and improved results are attainable in the practical use or application of the invention, both as a receptacle and table for camping, as well as for automobile tourists.

45 In the accompanying drawings forming part of this application:—

Figure 1 is a perspective view of the device folded in box position, showing a box end as being slid into position.

50 Fig. 2 is a perspective view showing a complete box with the lid closed.

Fig. 3 is a cross section as shown in Fig. 2.

Fig. 4 is a perspective view of a table and seat formed by the several box members.

55 Fig. 5 is a section taken on the dotted line A—A Fig. 4.

Fig. 6 is a detail perspective view of one of the end members.

Fig. 7 is a perspective view showing the box folded for containing the remaining elements.

Fig. 8 is an inverted detail perspective view of one of the table braces partly broken away.

The same reference characters denote the 65 same parts throughout the several views of the drawings.

In carrying out my invention I may employ wooden boards or other material in combination with metal binding flanges and 70 braces, but all the parts may be made of suitable metal, or other material of such character as will answer the purpose of producing a light weight, compact article capable of storing under an automobile or other 75 seat, and yet of such rigidity and strength as will permit of its use as a table and seats.

The box sides 1 and 2, the bottom 3, and the top or lid 4 are all hinged together as at 5 and 6. The hinges 6 connect a strip 7 with 80 the sides 1, and will be hereinafter particularly referred to. The sides, the strip, and the lid are grooved at 8, adjacent to the ends thereof for slidable box ends 9. Both of 85 said ends being of the same construction only one of them will be described in detail. The side edges have a projecting flange forming a tongue 10 fitting the grooves 8, and said edges are provided with an angle flange 11 overlapping said edges and forming 90 a binder for the box sides, as well as a groove or channel 10^a for the sides and the lid when the ends are slid into and out of box position.

The purpose and function of the strip 7 95 is to form the back of a case-like receptacle for retaining the box ends and other attachments for packing, storing or shipping as clearly shown in Fig. 7 of the drawings. The lid member is provided with a double 100 hinge fastening as 12, and the side member 2 is provided with a staple 13, for said fastening 12. Obviously the strip may be omitted and this side hinged directly to the bottom.

105 It will be understood that the lid, the side member 1, and the strip 7 are placed in alignment at right angles to the bottom member, and the side 2 is also held at right angle to the bottom member for adding the 110 end members, and the end members are slid endwise, first upon the lid member, and then

upon the side members and over the strip member into engagement with the bottom member, so as to leave the top of the end members flush with the side members, and 5 the lid free to be swung for opening and closing the box.

Obviously when the end members are slid out of position, the other box members are free to be opened into flat position. The box 10 lid member has removable hinge pintles 14, which are removed so as to disconnect the lid so that the latter may be used as a seat. The inner face of the lid is provided with screw sockets 15, for suitable legs 16. The 15 inner face of each of the box ends is provided centrally with a screw socket 17 for a suitable leg 18, so that the ends may be used as a seat or stool. The outer faces of the end members have hand-grasping means as at 20 19. The inner faces of the box side members have like sockets 19, for suitable legs 20, and these legs and members, which constitute the table top or board, are braced by angle braces 21, having U-shaped ends 22 fitting 25 the socket ends of said table legs so as to retain the braces in position. Other forms of sockets may be used.

Obviously the device may be used for various purposes both in folded and un- 30 folded positions, and I therefore do not wish to limit myself in this respect. I do not

wish to be understood as confining the invention to any particular size or material in the manufacture and practical application of the same, but reserve the right to make such changes and variations therein as may come within the scope of the appended claim.

Having thus described my invention what I claim as new and desire to secure by Letters Patent is:—

In a combination foldable knock-down box, table and packing case, a box bottom, a box side hinged to the bottom, a box side, a box lid hinged to this side, a hinged strip 45 connecting the bottom with this side, box end members having slidable engagement with the lid, the sides and the strip, the latter, the sides, the bottom and the lid adapted to be unfolded and again folded 50 into a packing case for retaining said ends, said sides, said strip and bottom adapted to be unfolded in flat position for forming a table top, and said ends and lid having leg sockets for forming seats, substantially as 55 set forth.

In testimony whereof I affix my signature in presence of two witnesses.

EDWIN P. WALKER.
